HANDBAG AND COVER THEREFOR

Warner R. Buxton, deceased, late of Longmeadow, Mass., by Mabel Allen Buxton, executrix, Longmeadow, Mass., assignor to Buxton, Incorporated, Springfield, Mass., a corporation of Massachusetts

Application December 22, 1941, Serial No. 423,992

5 Claims. (Cl. 150—28)

This invention relates to hand bags, such as purses, utility bags and the like, having removable covers.

One object of the invention is to provide a hand bag with a removable cover which may be quickly and easily removed to alter the color scheme or surface appearance of the bag.

A further object is to provide a combination of the above character of simplified construction which is adaptable to a wide range of hand bag constructions.

Other and further objects will be made apparent in the following specification and claims.

In the accompanying drawing which illustrates one embodiment of the invention:

Fig. 1 is a side elevational view of a hand bag provided with a removable cover in accordance with my invention, the cover being broken away at one corner;

Fig. 2 is an end view of the structure shown in Fig. 1;

Fig. 3 is a view similar to Fig. 2 but with the cover partly removed;

Fig. 4 is a view similar to Fig. 1 showing the hand bag with the cover removed;

Fig. 5 is a view showing the inside of the cover;

Fig. 6 is a fragmentary view, with parts broken away, showing the manner of securing the cover to the hand bag; and

Fig. 7 is a view similar to Fig. 1 but on a smaller scale and showing a modified form of cover.

Referring to the drawing, the hand bag proper or foundation bag is generally indicated at 10 and the removable cover at 11. The cover as best shown in Fig. 5 comprises a flat sheet of leather, fabric or the like 12, of size and shape to be folded around the bottom and side faces of the hand bag as shown in Figs. 1 and 2. Preferably as indicated in said figures the dimensions of the cover are made such that its edges extend slightly beyond the corresponding edges of the hand bag to mask the latter.

At each end of the cover sheet 12, on its inner face, is secured a piece 13, the end edge portion 14 of which is stitched as at 15 tightly to the cover sheet, leaving a free tongue portion 16. The sides of the free portion 16 are provided, adjacent the secured portion 14, with inwardly extending slits 17 forming outwardly extending ears 18.

The hand bag proper which may be of any usual construction as far as its closure and interior arrangement is concerned, is provided on each of its outer side surfaces with a pocket 20, the mouth 21 of which is closed adjacent each

end by short seams 22. The mouth of the pocket is spaced below the upper edge of the hand bag a distance *a* substantially equal to the dimension *b* of the secured portion 14 of piece 13, making allowance for the slight edge masking extension of the cover beyond the edges of the hand bag as previously mentioned. The cover 11 is releasably secured to hand bag 10 by folding the cover sheet 12 centrally about the bottom of the hand bag and inserting the free tongue portions 16 into the pockets 20 with the short seams 22 engaged in slits 17, the ears 18 being positioned beneath the short seams 22. The dimension *c* of the cover, that is the distance between the attached edges of flaps 16, is closely equal to the distance between the free edges of the pockets 20 measured around the bottom of the bag so that the pocket edges engage tightly in the bight of the flap to hold the cover snugly about the bag when the latter is either open or closed. The engagement of seams 22 in slits 17 not only holds the flaps in the pocket but also prevents endwise motion of the cover relative to the bag. By this arrangement the cover is securely but removably held in place.

As will be evident the insertion of the tongues 16 in pockets 20 does not in any way prevent access to or use of the said pockets and the hand bag can be used in the same manner with the cover in place as when it is removed. In one application of the invention the hand bag is made up with a permanent facing of a dark "utility" color and one or more of the removable covers in bright or light colors is provided for sport or dress accessories.

As will be obvious, the covers can be cheaply made from three pieces of leather or the like, and a number of covers of different colors to match or harmonize with a variety of colored costumes may be provided at a very reasonable cost. The invention also enables the dealer to meet the demand for a large range of colors without carrying a large and expensive inventory of hand bags.

While the cover has been described as made of leather, it will be understood that it could be made of fabric, stiffened if necessary by canvas or other reinforcing material, and its outer surface can be decorated by embossing or by embroidery, or otherwise embellished.

If desired, the cover may be made to extend only part way up the sides of the bag to leave a portion of the foundation bag exposed, as at 25 in Fig. 7, to provide a two color effect.

When the cover is made of leather no reen-

forcement other than that provided by the secured portion 14 is ordinarily required, the portion 14 giving a desirable rigidity along the edges of the bag opening.

Whatever the material used, this invention obviates the need of buttons, snaps or any other form of metal fastener.

What is claimed is:

1. A hand bag which comprises, a foundation bag provided on the outer surface of its front and rear sides with pockets opening toward the top, the mouths of said pockets being closed for a short distance adjacent each end, a cover sheet folded around the bottom of the bag and extending upwardly along the sides thereof, free tongue members extending downwardly from the upper ends of the cover sheet between the cover sheet and the adjacent side wall of the foundation bag and into said pockets, said tongues being provided with ears extending laterally beneath the said closed portions at the ends of the mouths of the pockets.

2. A hand bag which comprises a foundation bag provided on its front and rear sides with pockets opening toward the top, the mouths of said pockets being closed for a short distance adjacent each end, a cover sheet folded around the bottom of the bag and extending upwardly along the sides thereof, pieces secured to each end of the cover sheet, each of said pieces including a portion secured to the end portion of the sheet and a free portion, the said secured portion extending upwardly from the mouth of the adjacent pocket on the foundation bag and the free portion extending downwardly within said pocket, the free portion being provided with laterally extending ears engaging beneath the said closed portions at the ends of the mouths of the pockets.

3. A hand bag which comprises, a foundation bag provided on its front and rear sides with pockets opening toward the top, the mouths of said pockets being closed for a short distance adjacent their ends by a narrow seam, a cover sheet folded around the bottom of the bag and extending upwardly along the sides thereof, pieces secured to each end of the cover sheet,

each of said pieces including a portion secured to the end portion of the sheet, and a free portion, said secured portion being positioned above the mouth of the adjacent pocket on the face of the bag, the free portion extending downwardly within said pocket, the free portion provided with laterally extending slits in which said short seams are engaged, said slits forming laterally extending ears positioned below said short seams.

4. A hand bag which comprises, a foundation bag provided on its front and rear sides with pockets extending longitudinally from end to end of the bag and opening toward the top, the mouths of said pockets being closed for a short distance adjacent their ends by a narrow seam, a cover sheet folded around the bottom of the bag and extending upwardly along the sides thereof, pieces secured to each end of the cover sheet, each of said pieces including a portion secured to the end portion of the sheet, and a free portion, said secured portion being positioned above the mouth of the adjacent pocket on the face of the bag, the free portion extending downwardly within said pocket, the free portion provided with laterally extending slits in which said short seams are engaged, said slits forming laterally extending ears positioned below said short seams.

5. A removable cover for a hand bag having side pockets closed for a short distance adjacent their ends, said cover comprising, a cover sheet of material foldable around the bottom of the bag to extend upwardly along the sides thereof, pieces secured to each end of the cover sheet, each of said pieces including a portion secured to the end portion of the sheet, and a free portion, said secured portion forming a reinforcement along the ends of the cover sheet, said free portion being provided with laterally extending ears engageable within the side pockets of the bag and beneath the closed end portions of said pockets to releasably secure the cover to the bag.

MABEL ALLEN BUXTON.
Executrix under the Will of Warner R. Buxton,
Deceased.
